UNITED STATES PATENT OFFICE.

SAMSON D. WRIGHT, OF CLEVELAND, OHIO.

DUMP-CAR.

No. 906,088.

Specification of Letters Patent.

Patented Dec. 8, 1908.

Application filed June 24, 1908. Serial No. 440,108.

To all whom it may concern:

Be it known that I, SAMSON D. WRIGHT, a citizen of the United States, residing at Cleveland, in the county of Cuyahoga and State of Ohio, have invented certain new and useful Improvements in Dump-Cars, of which the following is a specification.

This invention relates to dump cars or conveyers and particularly to that type of dump cars in which the car body is tilted by turning or rolling the same on suitable bearing supports through an angle sufficient to permit the contents to fall or to be removed therefrom.

The invention relates particularly to dump cars of large size and capacity and has for its main object the provision of cars of the above type, which will be strong, rigid and durable, are well supported at all points, and are easily turned to dump or remove the contents.

In carrying out my invention I support the car body, the lower portion of which is preferably rounded or semi-cylindrical, at its ends on suitable uprights or standards carried by the frame and also provide roller supports for the car body intermediate its ends, whereby the weight is distributed and the turning or rolling is facilitated. The roller bearings referred to are preferably carried by the frame on cross sills and there may be as many series of rollers as is desired, the number depending generally upon the length and size of the car. The car body is provided with ways or tracks extending around the same and adapted to be engaged by the rollers, said ways being preferably in the form of channels secured to and extending around the lower part of the car body and the latter is braced on the interior in the plumes by the rollers by transverse walls or partitions which are preferably provided with perforations so that when the material contains liquid, said perforations will permit the liquid to seek its level.

The invention also relates in other aspects, to means for taking care of the end thrust of the car body and means whereby the weight of the car body and its contents is wholly or partially removed from the roller bearings when the car body is in its normal position.

My invention may still further be briefly summarized as consisting in certain novel details of construction and combination and arrangement of parts which will be described

in the specification and set forth in the appended claims.

For a better understanding of my invention reference is had to the accompanying drawings in which

Figure 1 is a side elevation of a portion of the car equipped with my invention, parts being broken away for the sake of clearness; Fig. 2 is a partial end elevation and transverse section of the same; and Fig. 3 is an enlarged partial transverse section substantially along the line 3-3 of Fig. 1 looking in the direction indicated by the arrows.

In the figures of the drawing, 10 represents the supporting frame provided with suitable car trucks 11 which are preferably of a standard type, and 12 the car body, which as will be explained is so supported and mounted that it may be turned or rolled on its supports preferably through an arc of 90 degrees so that the contents may be dumped or removed from the interior. The car frame 10 is preferably built up of rolled plates and angle sections and consists of two longitudinally extending side girders 13 and cross sills, which will be explained later. The frames are provided at the ends with upwardly projecting supporting frames or standards 14, which form the main supports for the car body, said standards being preferably built up of plates and angles and having a flat upper flange or surface 15 upon which bearing members of the car body rest and are adapted to roll in the dumping process. Located intermediate the ends of the frame are cross sills 16 each of which consists in this case of two spaced channel members 17, with the backs adjacent each other, and plates 18 which are secured to the backs of the channel members and which carry a series of roller bearings 19 for supporting the car body intermediate its ends in the turning or rolling operation. The number of these sills and series of rollers will depend largely upon the size and capacity of the car, in Fig. 1 of the drawing two series only being shown, a little less than half of the car being shown on said figure. The roller bearings 19 are mounted on studs 20, the ends of which are received in suitable recesses or bearings 21, of supporting members 22, extending longitudinally of the sill and secured to the sides of the plates 18 of the sill by bolts or rivets 23.

The car body 12 is built up of rolled plates and as here shown has a rounded or substan-

tially semi-cylindrical bottom portion 24, the sides at the upper part of the car body extending in this case upwardly a short distance beyond the curved or rounded portion 5 as shown at 25. The body is provided with hinged lids or covers 26 which may be locked in position by clamps 27. The ends of the car body are each provided with a bearing or supporting flange 28 preferably of cast metal, 10 which flange rests upon the top 15 of the corresponding standard 14 at the end of the frame. This flange, as is shown, is substantially U-shaped, the lower part being semi-circular, the circular portion being concentric with the rounded portion of the car body. 15 These flanges 28 are adapted to roll upon the upper surfaces of the standards and are each provided with a series of lugs or teeth 29 which engage corresponding holes or openings 20 in the top of the standard so that when the car body is being turned in the dumping process, they act somewhat similar to a gear and rack. The car body is provided with ways for the roller bearings, said ways consisting 25 in this case of channels 30, which are secured to the walls of the car body and which are rounded or curved in the arc of a circle concentric with the rounded portion of the supporting flanges at the ends of the 30 car body and as the car body is also rounded, the ways follow closely the contour of the rounded portion thereof. These channels 30 are located opposite all the series of rollers and engage the rollers during the turning or 35 rolling operation.

I provide on the interior of the car body in the plane of each series of rollers, means for bracing the car body, said means consisting in this case of transverse plates or partitions 40 31 which are secured to the car body by angles 32 located on each side of the plates and following the contour of the car body. These plates are preferably provided with a number of perforations 33 so that in case the 45 material carried, such as garbage for which this car is especially adapted, contains liquid, the latter may seek its level regardless in which section of the car the material is thrown. It will be seen that with this 50 form of bracing partition there will be no danger of any material carried by the car becoming entangled or caught as would be the case if other forms such as lattice work were employed.

55 Secured to the bottom of the car body are a number of plates or castings 34 each having a central, rounded lug or enlargement 35. Two of these members 34 are located over each cross sill 16 in a position such that when 60 the car body is in its normal upright position the lugs or enlargements engage the flanges of the channels of the cross sills and thus relieve the rollers directly under the center of the car body wholly or partially of the weight of 65 the car body and its contents. The lugs or

enlargements are so shaped however that as soon as the car body is turned from its normal upright position it rolls, so to speak, off said lugs and engages the roller bearings.

In order that the supporting flanges at the 70 ends of the car body may be relieved of the end thrust, which may be considerable in a car of this kind, particularly when loaded, I provide on the bottom of the car body on each side of the sills 16, short angles 36 having flanges 37 which extend downward below the sills and adjacent the flanges of the channels 17 thereof, so that in case the car body is shifted longitudinally the flanges of the angles engage the channels. For this 80 same purpose I provide on each end standard 14 adjacent the body of the car when in its normal position a plate 38 having an enlargement adapted to be engaged by the car body when the latter is shifted longitudinally.

I do not desire to be confined to the exact details shown but aim in my claims to cover all changes or modifications which do not involve a departure from the spirit and scope 90 of my invention.

Furthermore I do not desire my improvements to be limited to the particular type of car shown and use the word car in the specification and claims in its broad sense as applying to other forms of conveying vehicles.

Having described my invention, I claim:

1. In a dump car or vehicle, a supporting frame, and a body having a rounded bottom portion, said frame having uprights or standards on which the body is supported at its ends and on which it may be rolled, and roller supports for the body intermediate its ends.

2. In a dump car or vehicle, a supporting frame, a car body having a rounded bottom and rounded supporting projections at its ends, said frame having supports on which said rounded projections bear and roll when the car body is being tilted, and roller bearings engaged by the car body intermediate its ends during the rolling operation.

3. In a dump car, a frame having supports at its ends and cross members intermediate its ends provided with a series of roller 115 bearings, and a body adapted to turn on said bearings and having bearing portions at its ends adapted to rest and roll on said end supports.

4. In a dump car, a frame having at its 120 ends uprights or standards and cross sills intermediate its ends, each of said sills being provided with a series of roller bearings, and a car body adapted to turn on said bearings, and having at its ends portions resting and 125 adapted to roll on said uprights or standards.

5. In a dump car or vehicle, a supporting frame having at its ends upwardly projecting supporting standards and intermediate its 130 ends a cross member having a series of roller

bearings, and a car body adapted to rest and roll on said supporting standards and having a curved or rounded member extending around the bottom thereof and adapted to engage said rollers during the rolling operation.

6. In a dump car, a supporting frame having intermediate its ends one or more series of roller bearings, and a car body supported 10 at its ends on said frame in such a manner that it may be turned or tilted and having a channel member extending around the bottom thereof in the plane of each series of rollers so as to form ways or bearing members 15 for said roller bearings.

7. In a dump car, a supporting frame and car body, means for supporting the car body at its ends so that it may be turned or tilted, roller bearings for supporting the body intermediate its ends, and means for bracing the 20 interior of the car opposite said roller bearings.

8. In a dump car, a supporting frame, a car body having a rounded or semicylindrical 25 bottom portion, means for supporting said body at its ends, so that it may be turned or rolled, roller bearings carried by the frame and adapted to be engaged by the car body intermediate its ends, and a bracing wall or 30 partition on the interior of the body opposite the roller bearings.

9. In a dump car, a supporting frame, a car body having a rounded or semicylindrical bottom portion, means for supporting said 35 body at its ends, so that it may be turned or rolled, roller bearings carried by the frame and adapted to be engaged by the body intermediate its ends, and a bracing wall or partition on the interior of the body opposite 40 the roller bearings, said wall or partition having perforations to permit the passage of liquid from one side thereof to the other.

10. In a dump car, a frame, a car body supported on said frame at its ends in such a 45 manner that it may be turned or rolled, a cross member on said frame beneath the car body and having a series of rollers adapted to be engaged by the car body in the turning or rolling operation, and a device on the bottom of the car body engaging said cross member when the former is in its normal position so as to take the load off said rollers.

11. In a dump car, a supporting frame having a cross sill comprising two spaced 55 members having upper flanges, a series of roller bearings carried by said sill intermediate said members, a car body having a rounded or substantially semi-cylindrical bottom portion, said body being supported 60 by said frame at its ends and adapted to roll on said bearing, and means for removing the

weight of said body from said bearing when the body is in its normal upright position comprising members secured to the bottom of the body in position to engage the flanges 65 on said cross sill.

12. In a dump car, a supporting frame having cross sills provided with roller bearings, a car body having a rounded or semi-cylindrical bottom portion adapted to roll on 70 said bearings, means for supporting said car body at its ends, and means for receiving the end thrust of the car body comprising devices carried by the latter on each side of and adjacent said cross sills.

13. In a dump car, a supporting frame having at its ends uprights or standards and intermediate its ends a transverse member provided with a series of horizontally arranged roller bearings, and a car body provided at its ends with bearing projections having rounded or substantially semi-circular portions adapted to roll on said uprights or standards, and said car body having a rounded or substantially semi-cylindrical 85 bottom portion which is concentric with or has the same axis as the rounded or semi-circular portions of the bearing projections, and which engages the roller bearing during such rolling operation.

14. In a dump car, a supporting frame having at its ends uprights or standards and intermediate its ends a plurality of cross sills each comprising a pair of spaced parallel members, a series of horizontally arranged 90 roller bearings supported between the two members of each sill and having portions projecting above the same, and a car body having at its ends bearing projections which rest on and are adapted to roll over the upper ends of said uprights or standards, and said car body having a rounded or semi-cylindrical bottom portion engaging said roller 95 bearings during the rolling operation.

15. In a dump car, a supporting frame 100 having at its ends uprights or standards and having intermediate its ends transverse bearing or supporting members, and a car body having at its ends bearing projections which rest on and are adapted to roll over said uprights or standards and having a rounded or semi-cylindrical bottom portion which engages said bearing or supporting members 110 during the rolling operation, and transverse bracing walls on the interior of the car body 115 opposite said bearing or supporting members.

In testimony whereof I affix my signature in presence of two witnesses.

SAMSON D. WRIGHT.
